UNITED STATES PATENT OFFICE.

KENNETH E. STUART, OF PHILADELPHIA, PENNSYLVANIA.

TUNNEL.

1,040,811.

Specification of Letters Patent.

Patented Oct. 8, 1912.

Original application filed September 9, 1910, Serial No. 581,208. Divided and this application filed April 9, 1912. Serial No. 689,496.

To all whom it may concern:

Be it known that I, KENNETH E. STUART, a citizen of the United States, residing in the city of Philadelphia, county of Philadelphia, and State of Pennsylvania, have invented a new and useful Tunnel, of which the following is a specification.

My invention relates to a tunnel for an underground railway, and more particularly to a railway employed in the despatch of mail, parcels, etc., and for other purposes.

My invention resides in the construction and form of the tunnel section which is of a nature to give access to the interior of the tunnel while the cars are in operation or transit, and to render unnecessary any change in the shape or size of the tunnel section at curves where the tracks are banked.

20 My invention resides in the features hereinafter described and claimed.

For an illustration of one of the forms my invention may take, reference is to be had to the accompanying drawing, which 25 is a cross sectional view of my improved tunnel.

The tunnel is provided with channels S^{10} and S^{20} to accommodate two tracks for transit in opposite directions, with a passage S^{21} 30 between them carried down in the form of a trench T^2 and of suitable dimensions to permit a man to pass through.

The running rails R^3 are carried upon cross sleepers T^4 to which they are secured 35 as follows: On the inside they are bolted down by means of the dogs D^1 . The clips C^7 and tie rods B^7 draw the rails together against the dogs D^1 and at the same time hold the outer side down. The dogs D^1 40 resist the tendency of the rail to tip over outward and the clips prevent it from sliding. Both together hold it down, forming a very secure fastening which can readily be tightened from time to time by means of the nuts N^1 and N^2 and which obviate the necessity 45 of letting the sleepers project some distance beyond the rails.

The cross sleepers T^4 rest upon a longitudinal sleeper T^5 , which they overhang on 50 each side, thus utilizing the natural spring of the cross sleepers to absorb the shock of passing trains and relieve the concrete shell of the tunnel from a hammering that would be liable in time to start cracks.

55 The shape of the space occupied by the

cross and longitudinal sleepers lends itself to the form of tunnel section shown. The surface S^{22} is of circular section, struck from the center of figure of the car O^1 . This form gives a very thick section across Y , Y' , 60 which would otherwise be the weak section of the tunnel and also provides space in which the conduits C^8 , which contain electric power and telephone cables, can be accommodated. The circular form of the surface S^{22} also permits the track to be banked at the curves as shown in the dotted position, without changing the form of the tunnel sections. The space between the sleepers, etc., is filled with ballast and no anchor bolts or other fastenings are required, which 65 greatly facilitates the construction of the tunnel.

The shell of the tunnel is of concrete reinforced by expanded metal as follows: A 75 sheet R^7 is carried completely around the tunnel, occupying the neutral axis at the top where the stresses are compression only, and being carried close to the inner surface at the bottom and sides of the trench portion, where a separate sheet R^8 is placed 80 close to the outer surface. The rib Y^1 is reinforced by the sheet R^9 .

T represents a contact rail for delivering current to the motors upon the cars through 85 the sliding contacts C^1 .

This application is a division from my application Serial No. 581,208, filed September 9, 1910.

What I claim is:—

1. In a despatch system, a tunnel section having side channels to accommodate tracks for cars moving in opposite directions, and a passage away comprising a trench between 95 said channels, and an arched roof common to said passage way and to said channels.

2. In a despatch system, a tunnel section having channels to receive car tracks, said channels formed with a bottom of substantially circular section having as center the center of figure of the car adapted to run upon said tracks, whereby the tracks may be banked at curves without altering the tunnel section.

3. In a despatch system, a tunnel section having channels to receive car tracks, said channels formed with bottoms of substantially circular section having as center the center of figure of the car adapted to run 105 upon said tracks, whereby the tracks may be 110

- banked at curves without altering the tunnel section, and provided with a trackway in each of said channels comprising transverse sleepers, a longitudinal sleeper, said transverse sleepers resting upon and overhanging said longitudinal sleeper, and running rails secured upon said transverse sleepers.
4. A reinforced tunnel section having side channels and a trench between said channels, an arched roof common to said trench and channels, and reinforcing means occupying substantially the neutral axis of the arched roof and approaching the inner surface of the tunnel section at said channels.
- 10 5. A reinforced tunnel section having side channels and a trench between said channels, an arched roof common to said trench and channels, and reinforcing means occupying substantially the neutral axis of the arched roof and approaching the inner surface of the tunnel section at said channels and approaching the surface of a corner formed between a channel and said trench.
- 15 6. A reinforced tunnel section having side channels and a trench, an arched roof common to said channels and trench, and reinforcing means occupying substantially the neutral axis of said arched roof and extending around and beneath said channels and
- 20 7. A reinforced tunnel section having side channels and a trench, an arched roof common to said channels and trench, and reinforcing means occupying substantially the neutral axis of said arched roof and extending around and beneath said channels and
- 25 8. A reinforced tunnel section having channels and a trench, an arched roof common to said channels and trench, and reinforcing means disposed near the outer surface of said section beneath said trench and channels.
- 30 9. A tunnel section having channels and a trench, an arched roof common to said channels and trench, said channels formed with a bottom of substantially circular section having as center the center of figure of a car adapted to run through a channel, the tunnel section being thickened at the junction between trench and channel.
- 35 10. A tunnel section having channels and a trench, an arched roof common to said channels and trench, said channels formed with a bottom of substantially circular section having as center the center of figure of a car adapted to run through a channel, the tunnel section being thickened at the junction between trench and channel, and a conduit disposed in said thickened section.
- 40 In testimony whereof I have hereunto affixed my signature in the presence of the two subscribing witnesses.
- 45 KENNETH E. STUART.
